UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A SCONCE-FRAME.

SPECIFICATION forming part of Design No. 14,244, dated August 28, 1883.

Application filed July 16, 1883. Term of patent 7 years.

To all whom it may concern:

Be it known that I, ALBERT PATITZ, of Meriden, in the county of New Haven and State of Connecticut, have invented a new Design for a Sconce-Frame; and I do hereby declare the following, when taken in connection with accompanying drawing and the letters of reference marked thereon, to be a full, clear, and exact description of the same, and which 10 said drawing constitutes part of this specification, and represents a face view.

This invention relates to a design for metal frames for mirrors, commonly called "sconces;" and it consists in the configuration and ornamentation of the frame, as shown 15 in the accompanying illustration and herein-after described.

The two sides are composed of two parallel bars, leaving a space between, that space filled 20 with a floriated tracery representing daisies. Upon the outer bar of each side is a series of scallops. The top and bottom, which are alike, are composed of two horizontal parallel bars. At the center, between these bars, is a dia-

mond-shaped figure, on the face of which is a 25 rose ornament. Uprights between the two horizontal bars, each side the said central figure, form a central panel, and in which, from the sides of the diamond, spring floriated ornaments. At each side the central panel is a 30 floriated tracery representing daisies, as shown in the accompanying illustration.

I claim—

The herein-described design for sconce-frames, consisting of the two sides, composed 35 each of two parallel bars, the space between filled with a tracery representing daisies, with a series of scallops upon the outer bar of each side, the top and bottom composed each of two horizontal bars, having in a central panel a 40 diamond-shaped figure, and at each side of the panel a floriated tracery representing daisies, as shown in the accompanying illustration.

ALBERT PATITZ.
